UNITED STATES PATENT OFFICE

PAUL R. MILLER, OF NEW YORK, N. Y., ASSIGNOR TO THEO. J. LAPRES, INC., OF ATLANTIC CITY, NEW JERSEY

DESIGN FOR A CARTON

Application filed September 6, 1930. Serial No. 36,887. Term of patent 7 years.

To all whom it may concern:

Be it known that I, PAUL R. MILLER, a citizen of the United States, residing at New York city, in the county and State of New York, have invented a new, original, and ornamental Design for a Carton, of which the following is a specification, reference being had to the accompanying drawing, forming part thereof.

The figure is a perspective view of a carton showing my new design. The opposite side of the design is substantially the same as that shown in the present figure.

I claim:

The ornamental design for a carton, as shown and described.

PAUL R. MILLER.
